UNITED STATES PATENT OFFICE.

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKE-OVEN WALL STRUCTURE.

Application filed October 25, 1919, Serial No. 333,258. Renewed July 24, 1923.

To all whom it may concern:

Be it known that I, JOSEPH VAN ACKEREN, a citizen of the United States, residing in Pittsburgh, in the county of Allegheny and State of Pennsylvania, have invented a new and useful Improvement in Coke-Oven Wall Structures, of which the following is a specification.

This invention relates generally to coke oven structures and has for its essential object the provision of a joint between the end of the heating wall of the oven and the jamb facing the end of such wall, which joint accommodates itself to heterogeneous expansion or contraction of the heating wall and jamb, permitting such expansion or contraction without resistance, and yet preserves substantial gas-tight conditions under all circumstances, thus preventing leakage and waste of gas from the heating walls.

A further object of the invention is the provision of an exceedingly simple and efficient means for maintaining the jamb in its proper position at the end of the heating wall and for preventing endwise shifting of the jamb with respect to said heating wall.

In the accompanying drawing, forming a part of this specification, and showing, for purpose of exemplification, a preferred form and manner in which the invention may be embodied and practiced, but without limiting the claimed invention specifically to such illustrative instance or instances:

Figure 1 is a fragmentary side elevation of a coke oven structure provided with the present improvements.

Fig. 2 is a vertical section of the same taken in a plane indicated by the line 2—2 of Fig. 1.

Fig. 3 is an enlarged fragmentary horizontal section taken in the plane indicated by the line 3—3 of Fig. 4.

Fig. 4 is an enlarged fragmentary vertical section through the heating wall and jamb of a coke oven.

In its present embodiment, the invention is incorporated in a coke oven battery of the by-product type, and for convenience the present description will be confined to this

use of the invention. Features of the invention are however readily susceptible of other uses, for example, in connection with coke oven batteries of other types; hence, it is manifest that the scope of the invention is by no means confined to the specific use and specific embodiment herein described.

Referring to the drawings:

There is shown a fragment of a coke oven battery, said battery being, in the present instance, of the by-product type and embodying in its construction a plurality of coking chambers 11 arranged side by side and having the usual alternating heating walls 12 provided with flame flues 13 intermediate adjacent coking chambers. The ends of each coking chamber or oven are closed by the usual doors, not shown, but of any preferred construction well known to those skilled in the art, and when a charge within one of the coking chambers has been coked the door of such chamber is opened or removed, and the finished coke is pushed out of the chamber and disposed of in the usual way.

The heating walls 12 extend vertically to the top 14 of the coke oven battery, said top being of the usual construction, and facing the end of each heating wall 12 is a jamb 15 consisting essentially of a vertical wall section substantially co-extending along the end of the heating wall and formed of the usual jamb bricks, as shown. The outer face of each jamb 15 is braced by a pair of vertical buck stays 16 which extend vertically beyond the top 14 of the coke oven battery. It will be understood that the heating walls 12 extend crosswise of the coke oven battery and at their opposite ends are faced with jamb such as are indicated at 15, and that vertical buck stays are also provided for bracing the outer faces of the jamb on that side of the battery opposite to the side indicated in the drawing. The several pairs of buck stays on opposite sides of the coke oven battery are connected together by transverse bars 17 secured to cross heads 18 mounted adjacent the upper end of each pair of buck stays.

The present invention relates particularly to the provision of an improved joint con-

struction between the ends of the heating walls 12 and the adjoining jambs 15, which joint construction will accommodate itself to heterogeneous expansion or contraction of the heating wall and the adjoining jamb and yet will maintain substantially gas-tight conditions so as to prevent leakage into and from the heating walls. In accordance with the usual practice the heating walls 12 are constructed of liner-brick sections 19, 20 connected together at intervals by tie-brick sections, there being interior tie-brick sections 21 and end tie-brick sections 22 located at the ends of the heating walls. The flame flues 13 are located between the several tie-brick sections as shown. The several sections constituting each heating wall are constructed of silica brick, whereas the jambs 15 facing the ends of the heating wall are constructed of clay bricks. As a result of the facts that the heating walls and the adjoining jamb are formed of materials having different coefficients of expansion, that the jambs are exposed exteriorly to radiation, and that the buckstays exert variable pressures upon the jamb bricks during expansion or contraction of the battery, the problem of providing a joint which will maintain substantially gas-tight conditions between the ends of the heating wall and yet permit the heterogeneous expansion of the jambs and heating walls, when subjected to coking heat has, in the past, been exceedingly difficult of solution. Most adhesive materials when used as fillers between the jambs and the ends of the heating walls are unable to withstand the enormous strain produced by the heterogeneous expansion or contraction of these parts, and consequently crack under such stresses, leaving chinks and crevices which have made gas-tight conditions almost impossible.

The present invention obviates the aforesaid difficulties by the provision of a joint between the ends of each heating wall and the adjoining jamb, said joint being composed of a fluent solid substantially gas-tight material that is non-agglomerative when subjected to coking heat.

A satisfactory material for this purpose is silica sand which does not agglomerate or form itself into lumps when subjected to the temperatures at the joints, and such joints may be readily formed by filling the entire space between the jamb and the end tie-brick section 22 of the heating wall with silica sand, as shown at 23. When the heating walls and the jambs expand or contract heterogeneously the sand because of its fluent nature will run into and fill up any chinks, thus maintaining constant substantial gas-tight conditions without giving rise to cracking or otherwise damaging stresses.

The joint between each jamb and the end

of the heating wall is furthermore constructed to prevent endwise slipping of the jamb with respect to the heating wall. For this purpose the ends of the liner-brick sections 19, 20 of each heating wall are formed with jogged edges 24; the jambs 15 are formed with similar or companion jogged edges 25 for engagement with the jogged edges 24 of the heating walls; the inter-lock flanged and grooved faces of the jambs and heating walls will prevent endwise movement of the jambs and maintain the latter at all times in their proper positions at the ends of the heating walls. If desired, these companion jogged edges of the jambs and heating walls may be held together by silica or other suitable cement.

The invention as hereinabove set forth is embodied in a particular form of construction, but may be variously embodied within the scope of the claims hereinafter made.

I claim:

1. In a coke oven structure, in combination: a heating wall comprising spaced silica liner-brick sections connected together at intervals by silica tie-brick sections to form flame flues within said heating wall, the ends of said liner-brick sections being formed with jogged edges; a clay jamb-brick section positioned at the end of the heating wall and provided with companion jogged edges for engagement with the aforesaid jogged edges of the liner-brick sections; and a substantially co-extending vertical joint interposed between said jamb-brick section and the adjacent tie-brick section of the heating wall, said joint composed of silica sand, to accommodate heterogeneous expansion or contraction of the jamb-brick section and the heating wall; substantially as specified.

2. In a coke oven structure, in combination: a heating wall comprising spaced silica liner brick sections connected together at intervals by silica tie-brick sections to form flame flues within said heating wall, the ends of said liner-brick sections being formed with jogged edges, a clay jamb-brick section positioned at the end of the heating wall and provided with companion jogged edges for engagement with the aforesaid jogged edges of the liner-brick sections; and a substantially co-extending vertical joint interposed between said jamb brick section and the adjacent tie-brick section of the heating wall, said joint being composed of substantially gas-tight fluent solid material non-agglomerative by coking heat, to accommodate heterogeneous expansion or contraction of the jamb-brick section and the heating wall; substantially as specified.

3. In a coke oven structure, in combination: a heating wall comprising spaced liner-brick sections connected together at inter-

- vals by tie-brick sections to form flame flues within said heating wall, the ends of said liner-brick sections being formed with jogged edges; a jamb-brick section positioned at the end of the heating wall and provided with companion jogged edges for engagement with the aforesaid jogged edges of the liner-brick sections; and a substantially co-extending vertical joint interposed between said jamb-brick section and the adjacent tie-brick section of the heating wall, said joint composed of silica sand, to accommodate heterogeneous expansion and contraction of the jamb-brick section and the heating wall; substantially as specified.
4. In a coke oven structure, in combination: a heating wall comprising spaced liner-brick sections connected together at intervals by tie-brick sections to form flame flues within said heating wall; a jamb-brick section positioned at the end of the heating wall; and a substantially co-extending vertical joint interposed between said jamb-brick section and the adjacent tie-brick section of the heating wall, said joint composed of silica sand, to accommodate heterogeneous expansion and contraction of the jamb-brick section and the heating wall; substantially as specified.
5. In a coke oven structure, in combination: a heating wall comprising spaced silica liner-brick sections connected together at intervals by silica tie-brick sections to form flame flues within said heating walls; a clay jamb-brick section positioned at the end of the heating wall; and a substantially co-extending vertical joint interposed between said jamb-brick section and the adjacent tie-brick section of the heating wall, said joint composed of silica sand, to accommodate heterogeneous expansion and contraction of the jamb-brick section and the heating wall; substantially as specified.
6. In a coke oven structure, in combination: a heating wall comprising spaced liner-brick sections connected together at intervals by tie-brick sections to form flame flues within said heating walls; a jamb-brick section positioned at the end of the heating wall; and a joint interposed between said jamb-brick section and the adjacent tie-brick section of the heating wall; said joint being composed of substantially gas-tight fluent solid material non-agglomeratic by coking heat, to accommodate heterogeneous expansion or contraction of the jamb-brick section and the heating wall; substantially as specified.
7. In a coke oven structure, the combination with a heating wall and a jamb facing the end of said heating wall, the heating wall and the jamb having different coefficients of expansion, of a joint interposed between said jamb and said heating wall, and composed of sand, to accommodate the heterogeneous expansion or contraction of the jamb and the heating wall, substantially as specified.
8. In a coke oven structure, the combination with a heating wall and a jamb facing the end of said heating wall, the heating wall and the jamb having different coefficients of expansion, of a joint interposed between said jamb and said heating wall and composed of silica sand, to accommodate the heterogeneous expansion and contraction of the jamb and the heating wall, substantially as specified.
9. In a coke oven structure, the combination with a heating wall and a jamb facing the end of said heating wall, the heating wall and the jamb having different coefficients of expansion, of a joint interposed between said jamb and said heating wall and composed of substantially gas-tight fluent solid material non-agglomeratic by coking heat, to accommodate the heterogeneous expansion or contraction of the jamb and the heating wall, substantially as specified.
10. In a coke oven structure, the combination with a heating wall and a jamb facing the end of said heating wall, of a joint interposed between said jamb and said heating wall and composed of substantially gas-tight fluent solid material non-agglomeratic by coking heat, to accommodate heterogeneous expansion or contraction of the jamb and the heating wall, substantially as specified.
11. In a coke oven structure, the combination with a heating wall and a jamb facing the end of said heating wall, of a joint interposed between said jamb and said heating wall and composed of fluent sand, to accommodate heterogeneous expansion or contraction of the jamb and the heating wall, substantially as specified.
12. In a coke oven structure, in combination: a heating wall formed with jogged edges at its end; a jamb facing the end of said heating wall and provided with companion jogged edges for engagement with the aforesaid jogged edges of the heating wall; and a joint interposed between said jamb and said heating wall and composed of substantially gas-tight fluent solid material non-agglomeratic by coking heat, to accommodate heterogeneous expansion or contraction of the jamb and the heating wall; substantially as specified.
13. In a coke oven structure, the combination with a heating wall, of a joint interposed between said jamb and said heating wall and composed of substantially gas-tight fluent solid material non-agglomeratic by coking heat, to accommodate heterogeneous expansion or contraction of the jamb and the heating wall, and means for preventing

endwise shifting of said jamb with respect to the heating wall, substantially as specified.

14. In a coke oven structure, the combination with a heating wall and a jamb facing the end of said heating wall, of a joint disposed between said jamb and said heating wall and composed of fluent sand, to ac-

commodate heterogeneous expansion or contraction of the jamb and the heating wall, ¹⁰ and means for preventing endwise shifting of said jamb with respect to the heating wall, substantially as specified.

In testimony whereof I have hereunto set my hand this 8th day of October, 1919.

JOSEPH VAN ACKEREN.
